DESIGN FOR AN ASH TRAY

Russell W. Raine and George T. Derby,
Jacksonville, Fla.

Application September 27, 1946, Serial No. 133,608

Term of patent 7 years

(Cl. D85—2)

To all whom it may concern:

Be it known that we, Russell W. Raine and George T. Derby, citizens of the United States, residing at Jacksonville, in the county of Duval, and State of Florida, have invented a new, original, and ornamental Design for an Ash Tray, of which the following is a specification, reference being had to the accompanying drawing, forming part thereof.

Fig. 1 is a top plan view of an ash tray, showing our new design.

Fig. 2 is an elevational view thereof, and

Fig. 3 is a vertical sectional view thereof taken on line 3—3 of Fig. 1.

We claim:

The ornamental design for an ash tray, substantially as shown.

RUSSELL W. RAINES
GEORGE T. DERBY.
